UNITED STATES PATENT OFFICE.

ARTHUR DE LANNAG TWYEFFORT, OF NEWARK, NEW JERSEY, ASSIGNOR TO JAPAN IMPORT AND EXPORT COMMISSION CO., OF NEW YORK, N. Y., A CORPORATION OF NEW YORK.

DESIGN FOR A TOY.

48,535.

Specification for Design.

Patented Feb. 8, 1916.

Application filed April 15, 1915. Serial No. 21,618. Term of patent 7 years.

To all whom it may concern:

Be it known that I, ARTHUR DE LANNAG TWYEFFORT, a citizen of the United States, residing at 1126^a Broad street, Newark, New Jersey, have invented a new, original, and ornamental Design for a Toy, of which the following is a specification, reference being had to the accompanying drawings, forming a part thereof, and in which the figure is a perspective view of a toy showing my new design.

I claim—

The ornamental design for a toy as shown.

ARTHUR DE LANNAG TWYEFFORT.
